CARPET SWEEPER

Carl C. Parrish, Shelbyville, Ind., assignor to
Porter Steel Specialties, Shelbyville, Ind., a
partnership consisting of Enos Porter, Hester
Porter Fuller, George M. Parker, and Charles
M. Youart

Application December 20, 1937, Serial No. 180,693

18 Claims. (Cl. 15—41)

In the operation of carpet sweepers of the rotary brush type, the most effective relationship of the brush to the surface to be acted upon is one where the ends of the bristles of the brush rest comparatively lightly upon the surface. Such sweepers are ordinarily used on carpets and rugs, and variations in the texture and depth of nap thereof cause very material variations in co-action between the brush and the surface.

10 The object of my present invention is to produce a carpet sweeper of the rotary brush type wherein the brush is yieldably mounted in the casing in such manner as to yield, or be movable, vertically within the casing so as to automatically adjust itself relative to the surface to be operated upon in accordance with the character of that surface.

15 The accompanying drawing illustrates an embodiment of my invention.

20 Fig. 1 is a vertical section axially of one end of the brush and the immediately adjacent portions of the structure;

25 Fig. 2 a transverse section on line 2—2 of Fig. 1 at the plane of the inner surface of the dust plate;

Fig. 3 a view similar to Fig. 2 except that it is in the plane of the outer face of the dust plate; and

Fig. 4 is a fragmentary section on line 4—4 of Fig. 1.

30 In the drawing 10 indicates the main body of the casing provided, near each end, with an end wall 11 vertically medially slotted at 12. Secured to the outer face of each end wall, one at each side of slot 12, is a plate 13 upon which is slidably mounted two wheel plates 14 each having a pin 15 upon which is journalled a traction wheel 16. Each plate 14 is yieldably urged toward the adjacent slot by a suitable spring so that the aligned wheels 16, while vertically fixed relative to the casing, are yieldably urged toward each other for a purpose which will appear.

35 Removably mounted in each slot 12 is an inverted U-shaped plate or carrier 17, the outer arm of which is slidably mounted in guides G on the inner face of end plate P. Between the arms of carrier 17 is journalled the friction pulley 18, the circumference of which is interposed between and engaged by the circumferences of the two adjacent traction wheels 16—16. Pulley 18 is provided with an axial cup 19 the bottom of which is provided with an axial polygonal perforation 21 accessible through perforation 22 through the inner arm of the U-plate 17. Pivoted at 23—23 on the inner face of the inner

40 arm of U-plate 17 are two reversely arranged bell crank levers each comprising a vertical arm 24 and a horizontal brush-lifter arm 25. The adjacent ends of the two arms 25 are overlapped and the weights of these arms are such as to normally urge the vertical arms 24 inwardly toward each other.

45 Arranged between each pair of vertical arms 24—24 is a buffer ring 26, the external circumferential face of which is preferably of a soft material such as rubber and this ring normally rests upon and engages the inner overlapping ends of the two horizontal arms 25—25.

50 Overlying the buffer ring 26 and the bell crank levers is a dust plate 27 horizontally slotted at 28—28 to receive the pivot pins 23—23, and vertically slotted at 29 the horizontal dimension of slot 29 being equal to the internal diameter of the buffer ring and the vertical dimension of this slot being enough to permit the desired vertical movement of the brush, as will be made to appear.

55 The brush bristles 30 are carried by an axle 31 which, at each end, is ensmalled so as to be projectible through slot 29 of the dust plate 27 and into the bore of the buffer ring 26, said ring fitting said ensmalled portion but being freely rotatable relative thereto. Each end of axle 31 is axially bored at 33 and at the bottom of the bore is an axial cup 34 like cup 19. Extending between cup 34 and cup 19, and having non-rotative association therewith, is a shaft 35. Conveniently, each shaft 35 at its outer end may be associated with its cup 19 in such manner as to be normally axially retained therein, although preferably axially separable therefrom if desired. For this purpose, the outer end of shaft 35 is provided with a circumferential groove 39 near enough to the end of the shaft to be within cup 19 when in position and, mounted in this groove is a split 40 spring retaining ring so that, when the shaft is projected into cup 19, the retaining ring will be within the bottom thereof and will serve to normally hold the shaft in axial position relative to the cup but will permit withdrawal of the shaft 45 upon exertion of sufficient force.

60 The connection between each pulley 18 and the adjacent end of the brush axle 31 is such as to permit vertical and lateral movement of the brush without interference to proper rotary movement of the brush.

65 The lower end of the outer arm of each plate 17 is turned outwardly at 17' to form a finger-hold and the plate at this point is perforated at 32.

The traction wheels, at each end, are covered by the end plate P and attached to each of these plates is a depending spring latch finger 36, the lower end of which is projected through perforation 32. The latch is provided with a pin 36' adapted to enter perforation 38 and thereby releasably retain plate 17 in position.

With the parts in operative position, the brush rests upon the surface to be treated. If this surface is a yieldable surface, such as a rug or carpet, the traction wheels will more or less sink into that surface while the brush bristles ride freely on the surface and when the casing is moved in one direction or the other, the resistance to rotation of the brush, offered by engagement of the bristles with the surface, will tend to cause a lateral movement of the brush so that the buffer ring will act upon one of the adjacent vertical arms 24 to swing its horizontal arm upwardly and thus vertically lift the brush, the companion lever 24-25 swinging in the opposite direction, i. e., the weighted arm moving downwardly, so as to keep the vertical arm in contact with the buffer ring. This action provides a support for the brush of such character that the contact of the lowermost bristles with the surface to be treated will be purely a function of the weight of brush and the resistance offered by the surface to the rotary movement of the bristles and this positioning will be entirely independent of any depth to which the traction wheels may be imbedded in the surface being treated.

As a consequence, the brush action is uniform irrespective of the character of the surface which is being brushed.

Upon reverse movement of the casing, a similar action takes place in conjunction with the companion bell crank levers and, as the buffer ring permits freedom of rotation of the brush axle therein, any noise which might otherwise result from alternate engagement of the brush axle with the vertical arms of the bell crank levers, is eliminated.

It will be readily understood that, so far as brush position is concerned the buffer rings are not essential and that the brush axle might directly engage the vertical arms of the bell crank levers. It will also be readily understood that the dust plate may be omitted if desired without interfering with the self adjusting operation of the brush relative to the surface over which it is to be driven.

I have found that if the shaft is of the flexible type, there is some tendency for the brush to chatter and I therefore prefer a solid shaft as shown. The connections between this shaft, the driving pulley, and the brush axle, must, of course, be necessarily loose to permit the desired play of the brush transversely of its axis and therefore, in order to prevent noise at these points, I introduce a silencer in the form of a rubber ring 37 in each cup as shown in Fig. 1.

I claim as my invention:

1. In a carpet sweeper, the combination of a main casing, traction wheels supporting the casing, a rotary brush mounted within the casing and floatable within the casing both vertically and horizontally independent of downward pressure applied to the casing, movable brush-supporting means mounted within the casing and shiftable by reason of horizontal movement of the brush to cause vertical movement of the brush, and a driving train interposed between the brush and one of the traction wheels.

2. In a carpet sweeper, the combination of a main casing, traction wheels supporting the casing, an axled rotary brush mounted within the casing and floatable within the casing both vertically and horizontally independent of downward pressure applied to the casing, movable brush supporting means mounted within the casing and shiftable by reason of horizontal movement of the brush to cause vertical movement of the brush, a buffer element interposed between the periphery of the brush axle and said movable brush-supporting means, and a driving train interposed between the brush and one of the traction wheels. 5

3. In a carpet sweeper, the combination of a main casing, traction wheels supporting the casing, a rotary brush mounted within the casing and movable transversely of its axis both vertically and horizontally, a pair of bell-crank levers carried within the casing with their vertical arms alternatively engageable by the brush axle and their horizontal arms underlying the brush axle, and a driving train interposed between the brush and one of the traction wheels. 10

4. In a carpet sweeper, the combination of a main casing, traction wheels supporting the casing, a rotary brush mounted within the casing and movable transversely of its axis both vertically and horizontally, a pair of bell-crank levers carried within the casing with their vertical arms alternatively engageable by the brush axle and their horizontal arms underlying the brush axle, a buffer ring journaled on the brush axle between the said vertical arms, and a driving train interposed between the brush and one of the traction wheels. 20

5. In a carpet sweeper, the combination of a main casing, traction wheels supporting the casing, an axled rotary brush mounted within the casing and movable transversely of its axis both vertically and horizontally, a pair of bell-crank levers carried within the casing with their vertical arms alternatively engageable by the brush axle and their horizontal arms underlying the brush axle, a driving train interposed between the brush and one of the traction wheels, and a dust plate interposed between the bell-crank levers and the brush bristles and covering said bell-crank levers, said dust plate having a perforation through which the brush axle projects 30 and movable therewith transversely of the axis of the brush. 40

6. In a carpet sweeper, the combination of a main casing, traction wheels supporting the casing, a rotary brush mounted within the casing and movable transversely of its axis both vertically and horizontally, a pair of bell-crank levers carried within the casing with their vertical arms alternatively engageable by the brush axle and their horizontal arms underlying the brush axle, a buffer ring journaled on the brush axle between the said vertical arms, a driving train interposed between the brush and one of the traction wheels, and a dust plate interposed between the bell-crank levers and the brush bristles and covering said bell-crank levers and buffer ring, said dust plate having a perforation through which the brush axle projects and movable therewith transversely of the axis of the brush. 60

7. In a carpet sweeper, the combination of a main casing, traction wheels supporting the casing, an axled rotary brush mounted within the casing and floatable within the casing both vertically and horizontally independent of downward pressure applied to the casing, means with- 70

in the casing and engageable by the brush axle upon horizontal displacement transversely of its axis in either horizontal direction from normal medial position to cause upward movement of the brush axle, and a buffer element interposed between said last-mentioned means and the brush axle.

8. In a carpet sweeper, the combination of a main casing, traction wheels supporting the casing, an axled rotary brush mounted within the casing and floatable within the casing both vertically and horizontally independent of downward pressure applied to the casing, means within the casing and engageable by the brush axle upon horizontal displacement transversely of its axis in either horizontal direction from normal medial position to cause upward movement of the brush axle, and a buffer ring journalled on the brush axle in position to engage said last-mentioned means.

9. In a carpet sweeper, the combination of a main casing, traction wheels supporting the casing, a rotary brush mounted within the casing and floatable within the casing both vertically and horizontally, a normally fixed-axis driving pulley arranged between and in peripheral contact with an adjacent pair of traction wheels, a drive shaft, relatively loose polygonal connections between the ends of said shaft and the driving pulley and the brush axle respectively, and noise-absorbing elements interposed between the shaft and pulley and between the shaft and brush axle.

10. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis.

11. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis, a shaft having a relatively loose non-rotative driving connection with the driving pulley, and yieldable means normally holding the shaft against axial separation from the driving pulley.

12. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis, a shaft, and a noise-absorber element interposed between the shaft and pulley.

13. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis, and a dust plate overlying the bell crank levers and perforated to receive the axle of a rotary brush and laterally shiftable relative to the pulley axis.

14. A carpet sweeper unit comprising a car-

rier, a drive pulley journalled on said carrier, a pair of bell crank levers pivoted on the carrier in a plane transverse to the pulley axis and axially spaced from the pulley with vertical arms one at each side of the pulley axis and overlapping horizontal arms beneath the pulley axis, a shaft having a relatively loose non-rotative driving connection with the driving pulley, yieldable means normally holding the shaft against axial separation from the driving pulley, and a dust plate overlying the bell-crank levers and perforated to receive the axle of a rotary brush and laterally shiftable relative to the pulley axis.

15. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis, a shaft, a noise-absorber element interposed between the shaft and pulley and a dust plate overlying the bell-crank levers and perforated to receive the axle of a rotary brush and laterally shiftable relative to the pulley axis.

16. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis, and a buffer ring sleeveable upon the axle of a brush and lying between the vertical arms of the bell-crank levers, a dust plate overlying the bell-crank levers and buffer ring and perforated to receive the axle of such brush and laterally shiftable relative to the pulley axis.

17. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis, a shaft having a relatively loose non-rotative driving connection with the driving pulley, and yieldable means normally holding the shaft against axial separation from the driving pulley, a buffer ring sleeveable upon the axle of a brush and lying between the vertical arms of the bell-crank levers, a dust plate overlying the bell-crank levers and buffer ring and perforated to receive the axle of such brush and laterally shiftable relative to the pulley axis.

18. A carpet sweeper unit comprising a carrier, a drive pulley journalled on said carrier, a pair of bell-crank levers pivoted on the carrier in a plane transverse to the pulley axis and axially spaced from the pulley with vertical arms one at each side of the pulley axis and overlapping horizontal arms beneath the pulley axis, a shaft, a noise-absorber element interposed between the shaft and pulley, a buffer ring sleeveable upon the axle of a brush and lying between the vertical arms of the bell-crank levers, a dust plate overlying the bell-crank levers and buffer ring and perforated to receive the axle of such brush and laterally shiftable relative to the pulley axis.
